UNITED STATES PATENT OFFICE

2,584,205

CURTAIN

Nell S. Hicks, Decatur, Ga.

Application June 28, 1949, Serial No. 101,843

2 Claims. (Cl. 160—348)

1

This invention relates to a curtain, and more particularly to a tie back for maintaining a curtain in gathered condition.

The object of the invention is to provide a tie back for a curtain having a substantially vertical ruffle, the tie back being arranged and constructed so that the curtain can be maintained in gathered condition without the necessity of having the cord of the tie back passing around this ruffle.

Another object of the invention is to provide a tie back for a curtain having a substantially vertical ruffle, the tie back including a casing secured to the main body of the curtain, there being a cord or tape slidably arranged in the casing, and there being a ruffle mounted on this cord which is adapted to be folded over the casing when the ends of the cord are attached to a fastening whereby an efficient and attractive means is provided for maintaining the curtain in gathered condition.

A further object of the invention is to provide a curtain which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a front elevational view of the curtain, according to the present invention;

Figure 2 is a sectional view taken on the line 2—2 of Figure 1;

Figure 3 is a sectional view taken on the line 3—3 of Figure 1;

Figure 4 is a longitudinal sectional view through the tie back and curtain; and

Figure 5 is a fragmentary front elevational view, showing the curtain in gathered condition.

Referring in detail to the drawings, the numeral 10 designates a curtain for a window and the curtain includes a body member 11. Arranged along the upper horizontal edge of the body member 11 and secured thereto, is a ruffle 12, there being a similar ruffle 13 arranged contiguous to the lower edge of the body member 11. Suitable stitching 14, Figure 1, serves to secure the ruffle 14 to the body member 11. The curtain 10 is further provided with a substantially vertical ruffle 15 which is secured to the body member 11 by a suitable line of stitching 16.

The present invention is directed to a tie back whereby the curtain can be efficiently and attractively maintained in gathered position, as shown in Figure 5, the tie back serving to maintain the

2

curtain in gathered position without the necessity of having the cord of the tie back pass around the ruffle 15. The tie back comprises an elongated strap 17 which is secured to the body member 11 by suitable lines of stitching 18 and 19 and the strap 17 and body member 11 coact to define a casing for slidably receiving therein a cord or tape 20. Secured to one end of the cord 20 is a ring 21 which is adapted to be arranged in engagement with a nail or other fastening member that may be secured to the window frame. The strap 17 is inclined from the horizontal and the strap extends from the left vertical edge of the member 11 to the right edge thereof.

Slidably arranged on the cord 20 is a ruffle 23. An elongated strap 24 is secured to the ruffle 23 by suitable lines of stitching 25 and 26 and the strap 24 and ruffle coact to define a space therebetween for slidably receiving the cord 20. The ruffle 23 is adapted to overlie the strap 17 when the curtain is in gathered condition, as shown in Figure 5.

From the foregoing, it is apparent that a tie back for a curtain has been provided with which the curtain can be maintained safely and attractively in gathered condition. Thus, in use, the ruffle 23 is arranged in front of the strap 17. Then, the ring 21, and the other end of the cord 20 are arranged in engagement with a nail 22 or the like so that the curtain will assume the position shown in Figure 5. Further, the tie back is so constructed that the curtain will be maintained in gathered condition without having the cord 20 passing around the ruffle 15. This will enhance the attractiveness of the curtain and prevent damage thereto.

What I claim is:

1. In a curtain including a body member, and a substantially vertical ruffle secured to said body member, the improvement consisting of providing a tie back for maintaining said curtain in gathered condition, said tie back comprising an elongated strap secured to said body member and coacting with the latter to define a casing, said strap extending from a vertical edge of said body member to the inner edge of said vertical ruffle on the face of said body member, a cord slidably arranged in said casing, an attaching ring secured to one end of said cord, and a ruffle slidably mounted on said cord and adapted to overlie the casing on the face of the body member to retain the curtain in gathered condition when said ring and the other end of said cord are drawn and fixed to a support.

2. In a curtain, a body member, a horizontally

disposed ruffle arranged along the upper edge of said body member and secured thereto, a substantially vertical ruffle arranged along an edge of said body member and secured thereto, an inclined strap extending from a vertical edge of said body member to the inner edge of said substantially vertical ruffle, said strap having its longitudinal edges secured to the face of said body member whereby said strap and body member coact to define a casing, a cord slidably arranged in said casing and having a ring secured to an end thereof, an elongated ruffle having a strap secured thereto, said strap and last-named ruffle coacting to define a space therebetween for slidably receiving said cord and said curtain is retained in gathered position with said last-named

ruffle overlying the casing on the face of the body member when said ring and the other end of said cord are drawn and fixed to a support.
